RAILWAY BRAKE STRUCTURE

Ambrose C. Moore, Winnetka, Ill., assignor to
Chicago Railway Equipment Company, Chi-
cago, Ill., a corporation of Illinois

Application June 10, 1940, Serial No. 339,708

9 Claims. (Cl. 188—242)

The invention relates to the assembly of brake heads and brake shoes of railway brake beams in which the head usually includes a pair of center lugs and upper and lower toes spaced therefrom, and the shoe includes a center lug supported on the brake head lower center lug, the braking force being applied to the brake shoes through the forward faces of the head lugs and toes, and the shoe and head being held assembled by a tapered key which extends through openings in the head center lugs and in the brake shoe lug inserted between them.

In new equipment of correct dimensions and properly assembled the key is supposed to hold the head and shoe in contact with each other so that these parts form a single rigid unit. As the parts consist of castings which are not machined, close and accurate fits are unlikely, and, irrespective of the initial assembly of the parts, the continuous jarring and vibration of the vehicle, together with the working of the parts on each other due to such vibration and to repeated application and release of braking forces, tend to develop play between the parts with resulting pounding and sliding which wears away the brake head surfaces contacting with the brake shoe. This is objectionable and may cause misapplication of the brakes and necessitate replacement of the heads which otherwise would have an indefinite useful life.

The main object of the present invention is to improve the mounting of the brake shoe upon the brake head by the use of yielding inserts which will reduce or eliminate pounding between these parts.

Another object is to provide metal to metal contact between the shoe and the head when the braking force is applied, which may occur on an average of probably not over twenty-five times a day, and thereby avoid subjecting the resilient elements to excessive pressure which would soon destroy their resilient characteristics, particularly if the resilient elements are formed of rubber.

Another object is to retain the shoe and head and assembling key against play and possible loss.

These and other detailed objects of the invention, as will appear from the following specification, are attained by the structure illustrated in the accompanying drawing in which—

Figure 1 is a side view and longitudinal section through a brake head and shoe assembly embodying one form of the invention, the section

part being taken approximately on the line 1—1 of Figure 2.

Figure 2 is a front elevation of the structure shown in Figure 1 but with the shoe removed.

Figure 3 is a detail transverse section taken on the line 3—3 of Figure 1.

Figure 4 is a similar section but showing the parts when subjected to braking forces.

Figure 5 is a view and section corresponding to Figure 1 but illustrating another form of the invention.

Figure 5a is an enlarged detail section illustrating the structure indicated in Figure 5.

Figures 6 and 7 are similar details illustrating other forms of the invention.

The brake head has a central body part 1 with a pocket 2, adapted to receive the ends of the compression and tension members (not shown) of a truss type brake beam, and with recesses 3 and 4, either one of which may receive a brake hanger (not shown) by which the beam is suspended from the truck frame. The brake head includes the upper center lug 5, lower center lug 6, which receive the shoe lug 7 between them, upper toe 8 and lower toe 9, which engage the end portions of the shoe. Lugs 5 and 6 and toes 8 and 9 have the general contour and arrangement characteristic of this type of brake head.

Each lug and toe is shown recessed to receive a separately formed insert of rubber or rubber-like material. The insert 10 in the head upper center lug 5 has a body portion 11, seated in the shoe opposing recess of the brake head, a neck 12, and a button 13, seated in the key opposing recess of the head. Normally the outer faces of elements 11 and 13 will project substantially beyond the planes of the adjacent surfaces of the head, as indicated in dotted lines at 11a and 13a (Fig. 3), but when the tapered key 15 is driven through the apertures 16 and 17 therefor in lugs 5, 6 and 7, the insert will be distorted as the shoe and key approach the head surfaces until the parts are substantially in the relative position indicated in Figure 3, the recesses in the head being large enough to accommodate this distortion of the insert.

The insert, when distorted as just described, tends to hold the shoe spaced away from the head during normal operation of the vehicle and thereby eliminate numerous wear producing contacts to which these parts otherwise would be subjected. Also the high degree of friction between elements 10 and key 15, and the shoe prevents these parts from slipping over each other and prevents the key working upwardly and the

corresponding loosening of the shoe and head, and this result will follow even if an old and badly worn key is used in which case the key may not lie close against the head as shown in Figure 3.

The brake head lower center lug 6 is shown with an insert 40 applied to its horizontal shoe lug opposing face and with a similar but separate insert 40 applied to its upright shoe back opposing face. The shoe upper center lug 5 is shown with the single insert 10 seated in its shoe back opposing face and having an angular extension 18 around its downwardly facing portion and opposing the upper face of lug 7. Either arrangement may be used on either or both shoe lugs.

The shoe toes 8 and 9 are shown provided with inserts 19 similar to inserts 40, although of smaller area, but the heads 20 of inserts 19 do not engage the key and have no function except to retain the inserts in place.

The density of the inserts and the size of apertures 21 extending through the lug walls will be so proportioned that the heads 13 and 20 may be squeezed through the apertures, whereupon their normal expansion will serve to retain the inserts in the head.

Figure 5 illustrates another form of the invention in which rubber-like inserts 25 are received in recesses 26 in the brake shoe and function to absorb loose play between the shoe and the head and to resist pounding and wear between these members, as do the inserts mounted in the head as previously described, but when the brakes are applied, the rubber elements may be compressed and distorted until the opposing elements of the shoe and head contact each other.

Figures 5 and 5a also illustrate another type of resilient insert in the shoe central lug and normally supporting the same in the head. Springs 27 are seated in upwardly and downwardly facing recesses in the shoe lug and bear against blocks 29 slideable in the recesses. Blocks 29 may be of rubber but preferably are of metal with facings 30 of rubber or other non-metallic material bonded to their outer surfaces and disposed to engage the opposing faces of the head lugs.

A shank 28 extends through the shoe lug and blocks 29 and has its ends enlarged and slideable in blocks 29. The shank functions to limit the outward movement of the blocks.

Upon the application of the brakes, the friction between the shoe and the wheel will cause the shoe to move upwardly or downwardly, relatively to the head, until the solid portion of the shoe lug engages the upper or lower head center lug, thus relieving the yielding elements of the load. The yielding elements are mounted at opposite sides of the key 31 as are the elements 40 on the upper face of the head center lug shown in Figures 1 and 2.

Applicant is aware that the use of rubber between a brake head and shoe has been suggested previously, and in this connection reference is made to United States Durbin Patent 1,939,296 issued December 12, 1933, but the structure there disclosed is subject to objections in that all of the thrusts between the brake head and shoe is transmitted through the rubber blocks with the resulting deterioration of the blocks. Furthermore, the structure disclosed in said patent does not prevent but rather facilitates the working loose of the key by the play between the shoe and head.

While applicant has disclosed members retained in recesses in the head or shoe by overlapping flange-like elements, it is obvious that, if desired, an individual resilient member projecting from one face of a lug may be secured to the mounting part by a bolt 32, as shown in Figure 6, or a screw 33, as shown in Figure 7, or the rubber block may be bonded directly to the metal of the mounting part as indicated at 34 in Figure 7.

It is to be understood that any of the resilient elements referred to above may be used in lieu of any of the other resilient elements so far as the attainment of the main object of the invention is involved, and also that certain features described and illustrated may be omitted without departing from the spirit of the invention so far as the latter is embodied in the features retained.

The size, contour, location and other detailed construction of the inserts may be modified otherwise than as indicated herein without departing from the spirit of the invention, and the exclusive use of such modifications as come within the scope of the claims is contemplated.

What is claimed is:

1. In a railway brake head having a brake shoe opposing face provided with a recess, a rubber-like insert seated in said recess and normally projecting therefrom to yieldingly engage a brake shoe, the volume of said recess being substantially equal to the volume of said insert so as to completely receive said insert when braking forces are applied to the head and shoe.
2. In a railway brake head, a lug having a brake shoe contacting face provided with a recess, there being an aperture extending from the bottom of said recess to the opposite side of the lug, and an insert of rubber-like material seated in said recess and projecting outwardly therefrom to yieldingly engage a brake shoe and including a shank extending through said aperture and there flanged to engage said lug side to retain the insert in the head.
3. In a railway brake head, a lug including a brake shoe opposing face and a key opposing face, each of said faces having a recess, there being a cushion of resilient material seated in each of said recesses and projecting outwardly therefrom to yieldingly engage a shoe and key respectively, to absorb normal play between the head, shoe and key.
4. In a railway brake head, a lug including a brake shoe opposing face and a key opposing face, each of said faces having a recess, there being a relatively restricted aperture through said lug between said recesses, and an insert of rubber-like material having portions seated in said recesses, and projecting outwardly therefrom to seat a shoe and key respectively, and having a relatively narrow part connecting said portions through said aperture, one of said portions being distortable to pass through said aperture to provide for assembly of the insert with the lug.

5. In a railway brake head, a brake shoe mounting lug having an aperture for a shoe retaining key, there being a recess in said lug adjacent to said aperture, and an insert of rubber-like material seated in said recess and projecting therefrom to engage a key passed therethrough and to yieldingly resist relative movement of the key towards the lug and to frictionally resist movement of the key through the aperture.

6. In combination with a railway brake head and shoe, cooperating lug members on the head and shoe having opposing, substantially horizontal faces by which the shoe is supported on the head, one of said members having a recess in its face, a spring seated in said recess, and a follower thrust from said recess by said spring to yieldingly engage the face of the other member to absorb play between the members.

7. In combination with a railway brake head and shoe, cooperating lug members by which the shoe is supported on the head, there being upwardly and downwardly facing recesses in said shoe lug member and an aperture through said lug between the bottoms of said recesses, a shank piece extending through said recesses and apertures, a coil spring seated on the bottom of each aperture and surrounding said shank piece, and spring followers on said shank piece normally thrust from the faces of said lug member by said springs and arranged to contact the opposing lug member, whereby play between the head and shoe is yieldingly resisted.

8. In a railway brake head, a brake shoe mounting member with a shoe contacting surface, there being an element of rubber-like material secured to said member and arranged to project beyond said surface and to be compressed between the member and a shoe mounted thereon to prevent slippage of the shoe over said surface.

9. In combination, a railway brake head metallic member and a brake shoe metallic member mounted thereon, elements of yielding material supporting the shoe member on the head member when the head and shoe members are relieved of braking pressure but constructed to distort under adequate braking forces, said head and shoe metallic members having opposing faces normally spaced apart by the resiliency of said yielding elements but disposed to contact each other when said elements are distorted under adequate braking forces and thereby transmit thrust between the members directly through said faces.
